US00D541468S

(12) **United States Design Patent** (10) **Patent No.:** **US D541,468 S**
(45) **Date of Patent:** **** Apr. 24, 2007**

(54) **LIGHT FIXTURE LENS**

(75) Inventors: **John T. Mayfield, III**, Loganville, GA (US); **Gary D. Trott**, Eatonton, GA (US); **Carl T. Gould**, Boulder, CO (US); **Christopher L. Sharp**, Conyers, GA (US)

(73) Assignee: **Acuity Brands, Inc.**, Atlanta, GA (US)

(**) Term: **14 Years**

(21) Appl. No.: **29/215,614**

(22) Filed: **Oct. 21, 2004**

(51) **LOC (8) Cl.** **26-99**

(52) **U.S. Cl.** **D26/120**

(58) **Field of Classification Search** D26/120, D26/78, 87, 113, 131, 121, 122, 119, 118, D26/77, 75, 76, 128; 362/217, 223, 263, 362/225, 364, 224, 218, 147, 257, 317; D13/184, D13/110

See application file for complete search history.

(57) **CLAIM**

The ornamental design for a light fixture lens, as shown and described.

DESCRIPTION

FIG. 1 is a perspective view of a light fixture lens of the present invention;

FIG. 2 is a cross-sectional view of the light fixture lens of FIG. 1 taken along line 2—2 in FIG. 1;

FIG. 3 is a bottom view of the light fixture lens of FIG. 1; and,

FIG. 4 is a right side elevational view light fixture lens of FIG. 1, the left side being a mirror image.

FIGS. 1, 3, and 4 are broken away to indicate indeterminate length.
